CLAIM

The ornamental design for a food container, as shown and described.

DESCRIPTION

FIG. 1 is an upper, front perspective view of a food container showing our new design.

FIG. 2 is a lower, front perspective view thereof.

FIG. 3 is a front elevation view thereof.

FIG. 4 is a rear elevation view thereof.

FIG. 5 is a top plan view thereof.

FIG. 6 is a right elevation view thereof.

FIG. 7 is a bottom plan view thereof.

FIG. 8 is a left elevation view thereof; and,

FIG. 9 is an upper, front perspective view thereof, shown in a position of use with an exemplary cap.

Portions of the food container shown in broken lines form no part of the claimed design.

1 Claim, 5 Drawing Sheets
